EXPANSIBLE END LINK FOR A BRACELET OR SIMILAR ARTICLE

Murray L. Cowan, Norwood, Mass., assignor to
Textron Inc., Providence, R.I.

Filed May 5, 1970, Ser. No. 22,815

Term of patent 14 years

Int. Cl. D11—01

U.S. Cl. D45—4

FIG. 1

FIG. 2

FIG. 3

FIG. 4

FIG. 1 is a top plan view of an expansible end link for a bracelet embodying my new design with the links in contracted position;

FIG. 2 is a side elevational view thereof;

FIG. 3 is a perspective view thereof; and

FIG. 4 is a view similar to FIG. 1 with the links in an expanded position, portions of the conventional appearing bottom links being visible between the expanded top links.

I claim:

The ornamental design for an expansible link chain for a bracelet or similar article, substantially as shown and described.
